UNITED STATES PATENT OFFICE.

CHARLES KIBLER, JR., OF NEWARK, OHIO.

STOVE.

SPECIFICATION forming part of Letters Patent No. 357,961, dated February 15, 1887.

Application filed July 24, 1886. Serial No. 208,986. (No model.)

To all whom it may concern:

Be it known that I, CHARLES KIBLER, Jr., a citizen of the United States, residing at Newark, in the county of Licking and State of Ohio, have invented certain new and useful Improvements in Stoves; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a plan view with the top plate removed. Fig. 2 is a vertical section on line x - x , Fig. 1. Fig. 3 is a transverse vertical section on line y - y , Figs. 1 and 2.

This invention relates to improvements in box-stoves, the object being to construct a seven-plate box-stove in such manner that the pipe-collar may be situated on the rear part of the top plate of the stove instead of on the front part thereof, as is the usual construction, and so that a return-flue may be made to said collar from the flues running from the opening in the roof of the fire-box, thus keeping the heat and products of combustion a longer time between said top and roof, so that a certain degree of heat at the top of the stove may be produced with less fuel.

The invention consists in the construction and novel combination of parts, as hereinafter described, and pointed out in the claims.

The invention is a seven-plate box-stove, as will appear from the following description of parts.

Referring by letter to the accompanying drawings, A designates the base-plate of the stove, supported on the legs a , either flanged and bolted thereto or attached thereto by lugs and tongue in the usual well-known manner.

B is the extended front end of the base-plate, having formed in it the ash recess or pit B' covered, when the draft is lessened, by the removable plate b , as shown.

C C are the sides of the stove, having the outstanding lugs c on their lower edges, through which they are bolted to the base-

plate. The front edges of the sides are rabbeted to make close joints with the inwardly-bent side edges of the front plate, D, the lower edge of which is held in a groove of the base-plate. The rear edges of the sides are similarly rabbeted to make similar joints with the rear plate, E, the lower edge of which is similarly held in a groove in the base-plate. 55

F is the door, hinged over a suitable opening in the front plate and closing with a catch 60 of ordinary construction.

G is the roof-plate of the fire-box, formed below said plate by the sides, ends, and floor of the stove. The roof is retained in place by the screws or bolts g , which pass through proper 65 openings made centrally in its front and rear ends, and engage in threaded openings in lugs g' , standing inward from the front and rear plates. The said plates are also bound securely in place by the screws g . 70

H H are the flue-openings of the roof G, made at the corners of the rear ends.

I I are vertical longitudinal partial partitions on the top of the roof G. The said partitions run from the rear edge of the roof to 75 points near the front edge of the same, making, when the top of the stove is in place, the flues i and i' between the former, and the openings H entering the flues i at the rear end of the stove, but having no communication 80 with the central flue, i' . The partitions I can be either cast in one piece with the roof-plate G or made detachable therefrom.

K is the top plate of the stove, which is properly secured by bolts or otherwise upon 85 the top edges of the sides and ends, the said edges being rabbeted to make a close joint with the downwardly-flanged edges of the top plate.

L is the pipe-collar made in the top plate 90 near its rear edge and communicating with the central flue, i' , as shown. The base-plate, the two side plates, the two end plates, the roof-plate, and the top plate make in all seven plates. 95

The draft, as indicated by the arrows, is from the fire-box openings H forward through the flues i , and then rearward through the central flue, i' , thus retaining the heat longer under the top plate. 100

Having described this invention, what I claim, and desire to secure by Letters Patent, is—

1. In a seven-plate box-stove, the combination of the fire-box roof-plate G, having the flue-openings H at its rear corners, the top plate of the stove having the pipe-collar K, made centrally near its rear edge, and the partial partitions I, making the flues *i i* and *i'* between the said roof and top plate, the former of which partitions communicate with the flue-openings of the roof G and the latter with the pipe-collar, substantially as specified.

2. The herein-described seven-plate box-stove, composed of the base-plate A, the side

plates, C C, the front plate, D, provided with the door F, the rear plate, E, the top plate, K, provided with the pipe-collar L, the roof-plate G of the fire-box, provided with the flue-openings H H, and the partial partitions I I, forming the flues *i i'* between the top plate of the stove and the roof-plate of the fire-box, substantially as specified. 20

In testimony whereof I affix my signature in presence of two witnesses.

CHARLES KIBLER, JR.
